AZEL C. HOUGH, OF JANEVILLE, WISCONSIN.

SHUTTLE MECHANISM.

1,103,586.

Specification of Letters Patent.

Patented July 14, 1914.

Application filed November 26, 1913. Serial No. 803,309.

To all whom it may concern:

Be it known that I, AZEL C. HOUGH, a citizen of the United States of America, residing at Janesville, in the county of Rock and State of Wisconsin, have invented a new and useful Shuttle Mechanism, of which the following is a specification.

My invention relates to improvements in shuttle mechanism employed in weaving 10 shades, the weft of which consists of narrow fibers of wood or other substantial material, and resides in certain peculiar means or mechanism for acting on the shuttle jaws at the proper time to release the slat, fiber, or 15 weft-unit, carried thereby, and to thrust the same violently from said jaws downwardly into the shed of the loom, as herein-after more fully explained.

This invention is applicable to a loom 20 such as that described in United States Letters Patent, No. 764,290, and to a raceway and shuttle such as are employed in said loom, said shuttle being designed to carry the weft-units into the shed in the manner 25 set forth in said patent, but being in this case provided with additional parts or members, and the loom also being provided with additional parts and members, whereby the new results are produced.

30 The primary object of my invention is to place and deposit the slats forming the body of the fabric, or weft-units, quickly, accurately and positively in the shed of the loom, even though such weft-units be very 35 narrow and of insufficient weight to drop by gravity with the speed and accuracy necessary in order to produce the best results. With this mechanism weft-units of any width, even the narrowest, can be success- 40 fully handled, as before intimated.

Other objects and advantages will appear in the course of the following description.

I attain the objects and secure the advantages of my invention by the means illustrated in the accompanying drawings, in which—

Figure 1 is a front elevation in partial section of a practical form of embodiment 50 of my invention, the central portions of the loom elements therein shown, with the exception of the shuttle, being broken out; Fig. 2, an enlarged bottom plan of the shuttle, and, Fig. 3, an enlarged cross-section on lines 3—3, looking in the direction of the 55 associated arrow, in Fig. 1.

Similar figures refer to similar parts throughout the several views.

Although I have illustrated and will presently describe in detail a practical form of the invention, I do not desire or intend to be thereby restricted unduly, since my invention consists broadly of means, comprising a reciprocating shuttle provided with holding devices for firmly gripping a weft-unit, to carry such unit to the right position in the 60 shed, and then automatically to deposit said unit in the proper place in such shed, such last-mentioned means being adapted to open or separate said holding devices at the proper moment to release said unit, and at the same 65 time violently to thrust said unit from said holding devices into the shed immediately above other weft-units already woven after the first.

Since the shuttle travels from one end of 70 the raceway to the other and back again, carrying with it each time a weft-unit, the new mechanism is provided at and for each end of said shuttle, but one mechanism is 75 the duplicate of the other and entirely independent.

In the first view the front side of the raceway is entirely removed, and a portion of the body of the shuttle at the right-hand end is broken away to disclose fully the 80 mechanism provided at such end.

Referring to Figs. 1 and 2 of the drawings, it will be observed that there are there represented a raceway at 1, having inwardly-directed track plates or flanges 2—2 at the bottom, a tie-beam at 4, and a shuttle which is adapted to travel in said raceway on said flanges from end to end in both directions. Said shuttle comprises a body 5, having a bottom plate 6 with end projections or extensions 7—7, and provided at the ends underneath with gripping members, for the weft-units, consisting of resilient jaws 8—8 and 9—9. The body 5 is receivable between the sides of the raceway 1, and the plate 6 is provided adjacent to its longitudinal edges with shoes 10—10 adapted to slide on inwardly-projecting portions of the track plates or flanges 2. Each pair of jaws 8 and 9 is located beneath one of the extensions 7, and these are designed to have one end of a weft-unit, such as is shown at 11 in Fig. 1, forced between them, and firmly to grip and hold said unit and to carry it into the shed 105 of the loom, when the shuttle is projected 110

through the raceway 1 from one end to the other of said raceway. Each of the jaws 9 is secured to a lug 12 that extends downwardly from the bottom of the plate 6, while the 5 jaws 8 are formed by the terminals of a resilient strip 13 secured to a central lug 14 also depending from said plate. The parts and members thus far described are similar to corresponding parts in the herebefore-mentioned patent.

10 In each end of the shuttle body 5 is a slot 15, and pivotally mounted at 16 within said slot is a releaser and projector 17 for the weft-units. Each releaser and projector 17 has a cam edge 18 which extends above the slot 15 within which said releaser and projector is pivoted at its inner end, and such releaser and projector also has a finger 19 which extends out of the open 15 end of such slot and turns downwardly to project through an opening 20 in the adjacent extension 7. A stop 21, across each slot 15 near the outer end thereof and above the inner end portion of the finger 19 of the 20 releaser and projector within such slot, limits the upward movement of said releaser and projector which latter is normally held against said stop by means of a spring 22. Each spring 22 is received above the plate 25 6 in each recess 15, the sides of which latter are recessed, as indicated at 23 in Fig. 1, to accommodate said spring, and the latter is also received in a slot 24 in the releaser and projector which is actuated by said spring, a 30 tongue 25 depending from the top of said slot 24 to center the upper terminal of the spring. Normally the free end of each finger 19 contacts with the jaws 8 and 9 below, and the latter are cut out a little, as 35 shown at 26-26 in Fig. 3, to receive such end, and to facilitate the operation of said finger, as hereinafter explained. To the same end, the free terminal of each finger 19 is rectangular on the bottom or straight 40 across, as appears in Fig. 3.

Depending from the tie-beam 4, in the path of the cam edges 18 of the combined releasing and projecting members 17, are two actuating or depressing members or 45 dogs for said releasing and projecting members, each of such dogs being so located as to cause to be actuated the releaser and projector at the inner end of the shuttle, or the end of the shuttle last to pass through the 50 shed, just before said shuttle arrives at the end of its travel in either direction.

The releasing and projecting members 17 are relatively offset, as are the aforesaid actuating or depressing members therefor, the 60 arrangement being such that the left-hand actuating member is in the path only of the right-hand releaser, and depressor, and the right-hand actuating member is in the path only of the left-hand releaser and projector. 65 By this arrangement unnecessary friction,

action and wear are prevented. Provision should also be made to enable the aforesaid actuating members to swing inwardly or toward the center of the shed, so as not to interfere with the movement of the shuttle at the beginning of its travel. In short, the construction and arrangement of these parts should be such as to eliminate all unnecessary friction, action, wear, and loss of momentum.

70 Preferably each of the actuating members or dogs, for the releasing and projecting members, consists of a pair of arms 27 having their upper terminals pivotally attached at 28 to a lug 29 on the underside of the tie-beam 4, and carrying at their lower ends a roller 30 which is the contacting medium for the cam edge 18 into the path of which said roller is positioned by said arms. Normally each pair of arms 27 hangs perpendicularly from the pivot 28. An abutment pin or stop 31 projects from each lug 29 to prevent the arms 27 which hang from said lug from being swung out of the perpendicular by the associated releaser and projector 17 when it comes into contact with the roller 30 carried by said arms, at the time the shuttle approaches the end of the raceway 1. It will now be seen that, when the shuttle approaches either end of the raceway 1, the inner releaser and projector encounters the roller 30 which is in the path of the cam edge 18 of said releaser and projector, and that, 75 since the arms 27 which carry said roller are prevented by the contacting stop 31 from swinging outwardly, said releaser and projector is swung downwardly on its pivot 16, as it rides beneath said roller, and with its finger 19 forces apart the jaws 8 and 9 below and violently projects the weft-unit 11 downwardly into the shed. The releaser and projector 17 is thus depressed against the resiliency of its spring 22, and the latter acts to return said releaser and projector 80 to inactive position against the associated stop 21, as soon as the operating roller 30 is passed, and by the time the shuttle arrives at the extreme end of its travel in the direction in which it is assumed to be moving. When the shuttle is projected from the opposite end of the raceway, the releaser and projector which was just actuated is unaffected, because when it contacts with the roller 30 at that end of the loom 85 the arms 27 which support said roller are caused to swing inwardly on their pivot 28. Thus there is no opposition to the movement of the shuttle until just before it again arrives at the end of its travel, when the other releaser and projector is depressed by contact with the other roller 30, and another weft-unit is forcibly introduced into the 90 shed. Whenever either roller 30 and its arms 27 are actuated inwardly out of the 95 100 105 110 115 120 125 130

path of the contacting releaser and projector, said roller and arms return to position by gravity immediately after the passage of said releaser and projector, so that 5 normally said arms hang vertically alongside of their stop 31. This construction permits of the delivery by the shuttle into the shed of a continuous supply of weft-units, since said shuttle traverses the race- 10 way in both directions and can always carry a weft-unit with it for deposit.

In Fig. 1 the shuttle is represented as having traveled to the left far enough for the releaser and projector 17, which is to act on 15 the weft-unit 11 carried by said shuttle, to contact with the roller 30 which is in the path of the cam edge 18 of said releaser and projector. The weft-unit 11 has been carried through the shed almost into position to 20 be deposited therein, the exact position for deposit being reached at the instant the right-hand releaser and projector 17 is actuated downwardly by the roller 30 above, as the shuttle proceeds to the extreme limit of 25 its travel to the left.

In Fig. 2, the right-hand jaws 8 and 9 are shown fully open by the associated and contacting finger 19, as is the case when the right-hand releaser and projector 17 arrives 30 with the high part of its cam edge 18 directly beneath the contacting roller 30. Obviously, the thickness of the jaw-engaging portion of either finger 19 must exceed that of any weft-unit 11, if such finger is to 35 spread the jaws with which it coacts, as well as to force such unit from between said jaws. In some cases, however, the aforesaid jaw-engaging part might be of the same thickness as that of the weft-unit, or even poss- 40 sibly of less width.

Although this invention is practicable for wide weft-units, it is especially well adapted for weft-units which are too narrow to project beneath the spring jaws far enough 45 to be removed or knocked out by the means shown in said Patent, No. 764,290. This is clear when it is seen that, if the spring jaws were wide enough to hold firmly a weft-unit when it is carried swiftly through the race- 50 way, they would be too wide to permit a narrow weft-unit to project a sufficient distance beneath said jaws to be released in the old way and by the old means.

There is a sufficient amount of clearance 55 between the top of the plate 6 and of each extension 7 and the bottom of each releaser and projector 17 and finger 19, when said finger is raised against the stop 21 therefor, to allow for the necessary amount of move- 60 ment which said releaser and projector receives from the associated roller 30 at the time the shuttle carries said releaser and projector into position to deposit a weft-unit, such amount of movement being also suffi-

cient to open fully the jaws 8 and 9, with 65 which said finger is in engagement, and positively to thrust the weft-unit, held by said jaws, downward with the desired amount of force.

One of the dogs is omitted from the last 70 view for the sake of clearness.

It is believed the explanation already given of the operation of this invention will be found to be sufficiently clear without recapitulation. 75

What I claim as my invention, and desire to secure by Letters Patent, is—

1. The combination, with a shuttle, of the class described, provided with holding means for weft-units, and further provided with 80 means for positively ejecting such units from such holding means, of means capable of causing such detaching means to be actuated when said shuttle arrives at a predetermined place in its course. 85

2. The combination, with the raceway of a loom, of a shuttle for such raceway, such shuttle being provided with holding means for weft-units, and further provided with 90 means for positively ejecting such units from such holding means, and an actuating dog, for said detaching means, located in the path of the latter.

3. The combination, with the raceway of a loom, of a shuttle adapted to travel in 95 such raceway, such shuttle being provided with separable holding means for weft-units, and further provided with a spring-pressed member which has a part that projects into operative position relative to said holding 100 means and a weft-unit in the grasp thereof, and a dog in the path of said spring-pressed member, the arrangement of parts being such that, when said spring-pressed member encounters said dog, a weft-unit in the grasp 105 of said holding means is positively ejected therefrom.

4. The combination, with the raceway of a loom, of a shuttle for such raceway, such shuttle being provided with holding means 110 for weft-units, and further provided with means for positively ejecting such units from such holding means, and an actuating dog, for said detaching means, located in the path of the latter, and adapted to act upon the 115 latter only when the shuttle is moving in one direction.

5. The combination, with the raceway of a loom, a shuttle adapted to travel in such raceway, such shuttle being provided with 120 separable holding means for weft-units, and further provided with a spring-pressed member which has a part that projects into operative position relative to said holding means and a weft-unit in the grasp thereof, 125 of a swinging dog in the path of said spring-pressed member, and means to prevent such dog from moving in one direction out of an

approximately perpendicular position, the arrangement of parts being such that, when said spring-pressed member encounters said dog, a weft-unit in the grasp of said holding means is positively ejected therefrom.

6. The combination, with the raceway of a loom, a slotted shuttle adapted to travel in such raceway, such shuttle being provided with separable holding means for weft-units, 10 a spring-pressed releaser and projector pivotally mounted in the slot in said shuttle, and having a finger that extends into operative position relative to said holding means and a weft-unit in the grasp thereof, and 15 also having a cam edge, and a stop to limit the upward movement of said releaser and projector, of a dog arranged in the path of said cam edge, the arrangement of parts being such that, when said releaser and projector encounters said dog, a weft-unit in the 20 grasp of said holding means is positively ejected therefrom.

7. The combination, with the raceway of a loom, a slotted shuttle adapted to travel in such raceway, such shuttle being provided with separable holding means for weft-units, a spring-pressed releaser and projector pivotally mounted in said shuttle, and having a finger that extends into operative 30 position relative to said holding means and a weft-unit in the grasp thereof, and also having a cam edge, and a stop to limit the upward movement of said releaser and projector, of a swinging dog located in the path 35 of said cam edge, and means to stop the movement of said dog in one direction, the arrangement of parts being such that, when said releaser and projector encounters said

dog, a weft-unit in the grasp of said holding means is positively ejected therefrom.

40

8. The combination, with the raceway of a loom, of a reciprocating shuttle for such raceway, such shuttle being provided at each end with separable holding means for weft-units, and being further provided at 45 each end with a movable releaser and projector capable of being actuated to release and positively eject a weft-unit in the grasp of said holding means from the latter, the two releasing and projecting members being 50 relatively offset, and operating dogs arranged in the paths of said releasing and projecting members.

9. The combination, with the raceway of a loom, of a reciprocating shuttle for such raceway, such shuttle being provided at each end with separately holding means for weft-units, and being further provided at each end with a movable releaser and projector capable of being actuated to release and 55 positively eject a weft-unit in the grasp of said holding means from the latter, the two releasing and projecting members being relatively offset, and operating dogs arranged in the paths of said releasing and projecting 60 members, such dogs being adapted to swing each in one direction, so as not to act on the contacting releasing and projecting members when carried by the shuttle against said dogs in the directions in which they are 65 adapted to swing out of operative position.
